Primary Examiner — Kevin K Rudzinski*Assistant Examiner* — Paul D Bohannon(74) *Attorney, Agent, or Firm* — Hemingway & Hansen, LLP; D. Scott Hemingway(57) **CLAIM**

The ornamental design for an office bureau and hanging rack, as shown and described.

DESCRIPTION

FIG. 1 is a perspective view of my new office bureau and hanging rack design;

FIG. 2 is a front view of my new office bureau and hanging rack design;

FIG. 3 is a back view of my new office bureau and hanging rack design;

FIG. 4 is a left side view of my new office bureau and hanging rack design; and,

FIG. 5 is a left side view of my new office bureau and hanging rack design.

The broken line showing of a briefcase, computer pad device or mobile phone in the Figures is for the purpose of illustrating objects that may be supported on the claimed design and forms no part of the claimed design.

1 Claim, 4 Drawing Sheets(56)
